United States Patent Office.

ARTHUR D. MEDLICOTT, OF WINDSOR LOCKS, CONNECTICUT.

Letters Patent No. 71,199, dated November 19, 1867.

IMPROVEMENT IN SAFETY-HATCH FOR WAREHOUSES.

The Schedule referred to in these Letters Patent and making part of the same.

TO ALL WHOM IT MAY CONCERN:

Be it known that I, ARTHUR D. MEDLICOTT, of Windsor Locks, county of Hartford, and State of Connecticut, have invented certain new and useful Improvements in Safety-Hatches for Warehouses; and to enable others skilled in the art to make and use the same, I will proceed to describe its construction and operation by referring to the drawings, in which the same letters indicate like parts.

The nature of this invention consists in arranging slat-doors or platforms to wind up on to and off shafts, to open and close the space in the tube or box of an elevator by means or by the action of material or platform being raised or lowered therein. The object desired to be attained thereby is to render said box-secure from accidents of various kinds, to prevent persons from falling through said openings, as is often the case for the want of some protection; also, in such cases as where fire originates in one loft or story of a building, to cut off the draught, and thereby greatly retard its progress.

In the accompanying drawings is shown a vertical section of an elevator with the mechanism noted thereon.

a represents one side of the box-opening, near the centre of which is provided a depression or protuberance, or other convenient provision, to facilitate or guide the material or the platform upon which the material is placed to be elevated or lowered from one story to another. *b* are shafts, which extend across one or both open sides of the elevator, and in convenient proximity to the floor. The ends of these shafts take bearing in boxes *c*, near or on the edges of the sides *a* of the opening. *d* is a metallic slat-platform or door. The edges of these slats are secured together by links, so as to hold them uniform, one with the other, and so as to allow them to roll up and unroll on the shafts *b*. Each end of these slat-platforms traverses on or in ways or grooves formed on the inside or inner sides *a* of the opening. One edge of these platform slats is secured to the shafts *b*. *d'* are actuating-bars, one end of which is secured to cross-bars or sides *a*, so as to allow intermediate bars to be placed in the opening, when necessary or desirable, or to the sides near the opening. The other ends are secured in or so arranged as to actuate the platform backward when the material or article being raised or lowered strikes against said bars, their backward movement or winding process being facilitated by the joint action of the weights *e*, said weights being secured to the end of the cord, which has one or more turns around the end of and is secured to the shaft *b*. This platform is rendered self-closing by means of a cord, *f*, one end of which is secured to the inner edge of the platform, and the other end to the weight *g*, suitable friction-pulleys being arranged for these cords to work upon. *h* is a bale of goods, or a platform upon which material or articles are placed to be hoisted or lowered through the opening to or from one story to another in a building. Now, when this platform or bale is being lifted from one apartment to another, the body or sides thereof will strike against the bars *d'*, and by the joint action of the weights *e* the platform *d* will be actuated backward, and at the same time, by the action of the weights *e*, will be wound upon the shaft *b*, and as soon as the material or platform has passed the floor the slat platform will close up the opening by the action of the weights *g*. This rolling slat platform or door has great advantage over others; it is more compact and sure of operation.

I believe I have thus shown the nature, construction, and operation of this my improvement, so as to enable others skilled in the art to make and use the same therefrom.

What I claim, therefore, and desire to secure by Letters Patent, is—

The employment of the opening and closing rolling slat platform *d*, in combination with the shafts *b*, weights *g*, bars *d'*, and platform *h*, substantially as and for the purpose described.

ARTHUR D. MEDLICOTT. [L. s.]
